UNITED STATES PATENT OFFICE.

ROBERT C. ABT, OF CHICAGO, ILLINOIS.

DESIGN FOR A NUTCRACKER.

50,899.

Specification for Design. Patented June 12, 1917.

Application filed April 9, 1917. Serial No. 160,901. Term of patent 14 years.

To all whom it may concern:

Be it known that I, ROBERT C. ABT, a citizen of the United States, residing at Chicago, in the county of Cook and State of Illinois, have invented a new, original, and ornamental Design for Nutcrackers, of which the following is a specification, reference being had to the accompanying drawing, forming part thereof.

Figure 1 is a perspective view of a nut cracker illustrating my new design;

Fig. 2 is a side elevation of the same, a portion of the bowl broken away.

I claim:

The ornamental design for a nutcracker, as shown.

ROBERT C. ABT.
